(57) **CLAIM**

The ornamental design for a display screen or portion thereof having an icon, as shown and described.

DESCRIPTION

This application is related to U.S. Design application Ser. No. 29/658,973 and U.S. Design application Ser. No. 29/658,974, both filed concurrently with the present application, the disclosures of which are herein incorporated by reference.

FIG. 1 is a front view of a portion of a display screen showing a first embodiment of my new design for a display screen or portion thereof having an icon;

FIG. 2 is a front view of a portion of a display screen showing a second embodiment; and,

FIG. 3 is a front view of a portion of a display screen showing a third embodiment.

The wavy dashed-line rectangles illustrate the perimeters of portions of a display screen and form no part of the claimed design.

The remaining broken lines illustrate portions of the icon and form no part of the claimed design.
